UNITED STATES PATENT OFFICE.

CHARLES FR. TH. SALGER, OF CHICAGO, ILLINOIS.

CHANNEL-CUTTER.

SPECIFICATION forming part of Letters Patent No. 425,003, dated April 8, 1890.

Application filed October 25, 1889. Serial No. 328,191. (No model.)

To all whom it may concern:

Be it known that I, CHARLES FR. TH. SALGER, a citizen of the United States of America, residing at Chicago, in the county of Cook and State of Illinois, have invented certain new and useful Improvements in Shoe-Makers' Tools, of which the following is a specification, reference being had therein to the accompanying drawings.

10 This my invention relates to tools for boot and shoe makers for cutting the several channels and recesses into the in and out soles for boots or shoes, for securing the same by stitching to the welt and upper, which part of 15 the work heretofore generally had to be carried out with a common knife, requiring a very steady hand and considerable time for an accurate job, and it has been my object to provide a tool that can be adjusted to be the 20 proper gage, not only for the width and position of the channels and recesses to be cut, but also for the depth of the same, and which will thus greatly facilitate and accelerate this 25 part of the operation of shoe-makers; and with these objects in view my invention consists of the novel devices and combinations of devices hereinafter described, and specifically claimed.

In the accompanying drawings, Figures 1 30 and 2 represent side elevations, and Figs. 3 and 4 end elevations of the tool; Fig. 5, a longitudinal section through the center line of the tool; Fig. 6, a detached view of one of the locking-latches; Fig. 7, a cross-section on line 35 xx in Fig. 1; Fig. 8, a bottom face view of the insole; Fig. 9, a similar view of the outsole; Fig. 10, a cross-section of the outsole on line yy in Fig. 9; and Fig. 11 a cross-section of the sole portion of a boot or shoe on line zz 40 of Fig. 8, showing the connection of the parts.

Corresponding referential characters in the several figures of the drawings designate like parts.

The shank of this tool is composed of three 45 members, 1, 2, and 3, all made of metal, and the middle member 2 being provided with flanges 4 to its edges for holding part 3 in line therewith, and these three members being connected in about their middle by a 50 screw 5, passed through a slot 6 in member 3, through a hole in member 2, and tapped into

member 1, whereby the member 3 can be longitudinally adjusted relative to the other members. The member 2 has a head 6 integral therewith, which head is transversely 55 grooved in its middle, with a short squared projection 7 to one side and a longer tapering projection 8 to the opposite side of said groove, and with a slot 9 through head 6, extending angularly from the notch toward 60 the shank through the base of projection 8, and through this slot 9 is placed a knife 10, being adjustably secured therein by two set-screws 11, tapped through projection 8, and by a set-screw 12, tapped through the head 6 65 from the opposite side thereof to be central between the two set-screws 11. This knife 10 thus secured will occupy an angular position relative to the face of projection 7, with its cutting-edge projecting beyond such face of 70 projection 7 the desired distance the channel 13 in the bottom of the outsole 14 is to be cut, whereby the projection 8 will be guided against the edges of the sole 14 for gaging the distance the channel 13 is to be 75 from such edges.

The end of member 2 opposite to its head 6 has in one face a recess for inserting therein one shank of an L or angularly shaped knife 15, while the end face opposite to such recess 80 of member 2 is chamfered toward knife 15.

The part 16 of member 1, adjoining knife 15, is shaped rectangular with a blunt or stubbed end, and the knife 15 is clamped between the end faces of members 1 and 2 by 85 a screw 17, tapped into member 2 and passed through a hole in member 1 of the shank. This screw 17 being larger in diameter under its head, it provides a shoulder that bears upon member 1 for contracting the parts, 90 while this larger diameter portion provides the pivot for a plate 18 to swing thereon, and to be either turned toward the shank of the tool, as in Fig. 1, or to be in line with part 16 of shank 1, as shown by Figs. 2, 3, and 5, 95 with its exterior end extending beyond this end of part 16, where it is securely held by having a projecting nose 19 entering a notch 20 of part 16 of such shank 1 and by a turn-buckle 21, pivotally secured against the edge 100 of end 16 by a screw 22, tapped therein and turned to overlap the edge of plate 18.

The end of member 3 of the tool-shank butts against the inner face of the outer shank of knife 15, and is fitted to provide a true bearing for such knife end to rest against. 5 This member 3, a short distance above its end, is provided with an eye-lug 23, against which eye-lug by a rivet is pivotally secured the eyed end of an L-lever 24 to swing thereon, the shorter angular shank of which L-lever 10 24 will turn over the end of the knife 15, and will be locked on this position by a turn-buckle 25, pivotally secured against the end face of member 3 by a screw 26, tapped into member 3 so as to swing thereon, which turn-buckle 25 has to its swinging end a rectangular flange 27, that with being turned outward will grasp the edge of lever 24, holding it from swinging and against lateral lost motion. For turning L-lever 24 to release and 15 20 clear the knife 15, the turn-buckle 25 must be turned inward to be in line with the center line of the shank, and for enabling such movement a segmental groove 28 is formed in the edge of L-lever 24, and is continued 25 in the end face of member 3 for clearing the flange 27 during the swinging movement of turn-buckle 25.

A set-screw 29, tapped through member 3, near the fulcrum of L-lever 24, and butting 30 with its point against member 2 of the shank, is for adjusting the width of knife 15 to be exposed by L-lever 24, by spreading the members 2 and 3 more or less, for which purpose the screw 5 must first be loosened, and then 35 after such adjustment must be drawn tight again, while, as already described, the slot 6 in member 3 will permit longitudinal adjustment of member 3 for varying the distance of the cutting-edge of the knife 15 beyond the 40 stub end of part 16 of member 1.

The insole 30 for a boot or shoe is first to be formed in its lower face with a marginal recess 31, extending to the heel portion of such insole, which is accomplished with my tool 45 by adjusting it, as shown by Fig. 1, with the plate 18 swung back, when that part of lever 24 projected over knife 15 will provide the guide-shoulder to follow the edge of the sole 30, and the stub end 16 of member 1 will form 50 the gage for the depth the knife 15 is to reduce the sole 30. By this operation the corner of knife 15 will leave a shoulder 32, which for the next operation will be the guide for the tool for cutting a recess 33 in the inward face 55 of sole 30. For this purpose the L-lever 24 is first released from turn-buckle 25, and is then swung to clear knife 15, and then the plate 18 is turned outward and locked by turn-buckle 21, all as shown by Fig. 3, the project- 60 ing edge of which bar 18 will now be the guide to be moved along the shoulder 32, with the knife 15 reducing the insole to the depth the butt-end 16 will permit, thus leaving a ridge 35 on the sole of equal width and uniform 65 distance from the outer edge of sole 30. Under the margin 31 of insole 30 is secured the

edge of the upper 36 and of the welt 37 by transverse stitching through the ridge 35 from edge 34 to edge 32, and to the welt is then secured the outsole by stitching through the 70 channel 13 of such outsole, which stitches afterward are covered and protected by closing the channel 13 in the usual manner. It will thus be readily seen that this tool is complete in itself for the several operations necessary for channeling and recessing the soles of boots or shoes, which work can thus be performed in the most accurate manner. 75

What I claim is—

1. In a tool for the purpose described, the 80 combination of the members 1, 2, and 3 of the shank or handle adjustably connected by screw 5, of L-shaped knife 15, secured to member 2, and of L-shaped lever 24, secured to member 3 and overlapping knife 15 to provide a gage or guide shoulder, substantially as set forth. 85

2. In a tool for the purpose described, the combination of members 1, 2, and 3 of the shank or handle connected and relatively ad- 90 justed by screws 5 and 29, of L-shaped knife 15, secured to member 2, and of L-shaped lever 24, pivotally secured to member 3 and overlapping knife 15 to provide a gage or 95 guide shoulder, and of turn-buckle 25, for locking the same, substantially as set forth.

3. In a tool for the purpose described, the combination of members 1 and 2 of the shank or handle rigidly secured together, of L-shaped knife 15, clamped between the ends of 100 members 1 and 2 to extend from one side of stub end 16 of member 1, and of plate 18, secured against the opposite side of such stub end 16 to provide a guide or gage shoulder thereto, substantially as set forth. 105

4. In a tool for the purpose described, the combination of members 1 and 2 of the shank or handle rigidly secured together, of L-shaped knife 15, clamped between the ends of members 1 and 2 to extend from one side 110 of stub end 16 of member 1, of plate 18, pivotally secured against the opposite side of stub end 16, to provide a guide or gage shoulder thereto, and of turn-buckle 21, for locking the same, substantially as set forth. 115

5. In a tool for the purpose described, the combination of members 1, 2, and 3 forming the handle and secured together by screw 5, of L-shaped knife 15, clamped between the ends of members 1 and 2, of L-shaped lever 120 24, pivotally secured to member 3 and overlapping knife 15, of turn-buckle 25, for locking lever 24, of guide-plate 18, pivotally secured to member 1, and of turn-buckle 21, for locking guide-plate 18, all substantially as 125 set forth.

6. In a tool for the purpose described, the combination of members 1, 2, and 3, secured together by a screw 5, and the member 3, longitudinally and laterally adjustable on 130 screw 5, and by a set-screw 29, of member 2, provided with head 6, having gaging and

guiding projections 7 and 8, and being slotted for an adjustable knife 10, secured by set-screws 11 and 12, of L-shaped knife 15, clamped between the ends of members 1 and 2, of L-shaped lever 24, pivotally secured to member 3 and overlapping knife 15, of turn-buckle 25, for locking lever 24, of guide-plate 18, pivotally secured against stub end 16, of mem-

ber 1, and of turn-buckle 21, for locking plate 18, all substantially as set forth. 10

In testimony whereof I affix my signature in presence of two witnesses.
